UNITED STATES PATENT OFFICE

JOHN F. HALLADAY, OF RIVER FOREST, ILLINOIS, ASSIGNOR TO CONTAINER CORPORATION OF AMERICA, OF CHICAGO, ILLINOIS, A CORPORATION OF DELAWARE

BOX

Application filed November 10, 1930. Serial No. 494,609.

The invention relates to improvements in containers, and more particularly display boxes or packages of a type that the goods packed therein may be adequately displayed through a transparent dustproof covering without opening the package.

According to the preferred embodiment of the invention, the box comprises two separate paper or card board parts, one an inner collapsible tray and the other an outer band member adapted to fit snugly around the tray. In assembling the package the inner member is first filled with the material or articles to be packaged, then a sheet of cellophane or other transparent material is laid over the open top of the tray, the outer band is slid into place, and the package is complete, the outer band serving to hold the cellophane sheet in position and serving also to reinforce the inner tray.

The principal object of the invention is to produce an improved display box combining the features of simplicity and cheapness of manufacture, convenience and adaptability for shipment, assembly and packing, attractiveness of the finished package, and suitability for the display of the contents.

The invention will be more readily understood by reference to the accompanying drawings setting forth an illustrative embodiment thereof.

In the drawings,

Fig. 1 is a perspective view of the assembled package, portions thereof being broken away to more clearly disclose the details of construction;

Fig. 2 is a transverse vertical section on line 2-2 of Fig. 1, but on an enlarged scale;

Fig. 3 is a perspective view on a reduced scale of the outer reinforcing band, which serves to hold the cellophane sheet in position;

Fig. 4 is a plan view on a reduced scale of the inner tray shown in collapsed position for shipping purposes; and

Fig. 5 is a plan view on a reduced scale showing the blank from which the inner tray is formed.

Referring to the preferred embodiment

of the invention, the complete display package comprises three separate parts, namely, an inner collapsible tray generally designated by the reference character A, a transparent sheet B of cellophane or other suitable material adapted to cover the open or partially open top of the tray to keep the contents thereof fresh and to protect the same from dust, and an outer band member C, which in the assembled package surrounds the inner tray and holds the transparent sheet in position. Each of the three parts may be separately shipped flat, the inner tray and the outer band being of knock-down or collapsible construction. However, when the parts are assembled, each serves to reinforce the other, thus providing a container safe for shipping purposes. Ordinarily the package as a whole is wrapped with a suitable covering, not shown, adapted to withstand the rough handling incident to shipping. The top of the inner tray is at least partially open, permitting adequate display of the contents. In some instances the top may be entirely open, the cellophane sheet and reinforcing band being sufficient to hold the package in rigid position. In other instances the top is partially closed by cover portions which may be formed integral with the sides of the collapsible tray. These cover portions may serve to further reinforce the package.

The blank from which the inner collapsible tray is formed according to a preferred embodiment of the invention is shown in Fig. 5, and the tray in collapsed form is shown in Fig. 4. Referring particularly to these figures, the reference numeral 10 denotes the portion of the blank from which the bottom of the box is formed. End members 11 and 12 are hingedly connected thereto, being separated by score lines 13 and 14. The side members are indicated at 15 and 16, score lines 17 and 18 separating the sides from the bottom.

The side member 15, as shown, is provided with two end flaps 19 and 20, the length of which is preferably substantially one half the width of the ends 11 and 12. If desired, the flaps may be less than one-half the width

of the end members, but preferably should not be greater than one-half. The end flaps 19 and 20 are connected to the sides by means of score lines 21 and 22, and are separated 5 from the ends 11 and 12. The side member 16 is likewise provided with end flaps 23 and 24 connected thereto by score lines 25 and 26, the flaps 23 and 24 preferably corresponding in size and position to the flaps 10 19 and 20.

Although not necessary according to certain embodiments of the invention, according to the construction herein illustrated, the sides 15 and 16 have connected thereto by 15 score lines 28 and 30 respectively, partial closure members 27 and 29. As shown, the member 27 has formed integral therewith a fastening flap 31 terminating in a tab 32 separated from the main body of the flap 20 by a score line 33. To permit collapsing of the tray after the same has been assembled and glued, diagonal score lines are provided, which extend from the score lines 13 and 14 across the side flaps 15 and 16 and partial 25 closures 27 and 29. As shown, score lines 35 and 36 cross flaps 15 and 27, while score lines 37 and 38 extend across flaps 16 and 29.

The blank having been formed, the box 30 may be assembled on the conventional box gluing machines, and may be shipped, after assembly, in knock-down condition. To assemble the box, the ends 11 and 12 and sides 15 and 16 are folded up and the tabs 19, 20 and 23, 24 are folded inwardly and glued in 35 position to the ends 11 and 12, as indicated in Figs. 1 and 4. For shipping flat, the glued box is collapsed, being folded along lines 13 and 14 and diagonal lines 35, 36, 37 and 38, the form of the collapsed box 40 being illustrated in Fig. 4. It will be noted that the ends 11 and 12 are folded inwardly, while portions of the sides and closure members are folded outwardly along the lines 17 and 18, the remainder of the sides and end 45 members being folded inwardly upon themselves along the diagonal score lines.

When the tray arrives at its destination it is again formed into a box by folding up the sides and ends, whereupon suitable filling material is placed within the box. It will be noted that the filling material itself tends to press against the ends of the tray, thereby holding the same against collapsing 55 along the diagonal lines. After filling, the partial closure members 27 and 29 are folded over and the tab 32 is inserted in a slot 34 which is formed in the juncture line 30 connecting the flap 29 to the side 16. The 60 tab 32 extends within the side 16 just outside the contents of the box, as clearly indicated in Figs. 1 and 2. The closure serves to reinforce the tray, and if desired, the package might be wrapped in this form, preferably 65 with suitable transparent covering, and

shipped without the use of any further reinforcing means. It will also be noted that the partial closure 29 might be omitted and the flap 32 inserted between the side 16 and the contents of the box.

According to the preferred embodiment of the invention, however, the tray having been filled and the partial closure applied as described above, the transparent sheet or cover B of cellophane or other suitable material is placed over the top, the edges thereof preferably extending beyond the borders of the top of the tray. The outer band C is now applied, serving to hold the cellophane cover in place and acting further as 70 a reinforcement for the inner tray. As shown in Fig. 3, the outer band comprises a rectangular member scored at its four corners 41, 42, 43 and 44. The ends of the band may be suitably secured together as 75 by gluing at 45. Obviously the bands may be collapsed similarly to the tray and shipped flat.

When the package is complete, the contents of the box are constantly visible 80 through large triangular transparent spaces 39 and 40. According to the broadest aspects of the invention, the top may be entirely open, but according to the preferred embodiment, partial closures are employed 85 which serve to strengthen the package and at the same time leave large portions of the 90 contents visible.

The details of the package may be varied if desired within the scope of the invention. 95 The advantages of the device are many, one being that the goods packed in a container of this type may be adequately displayed without opening the package. Other advantages are that the box may be shipped 100 in knock-down condition, and that the tray may be made on the conventional box gluing machines without alterations. The container may be readily set up and securely sealed in practically air-tight condition 105 without the use of staples or glue, so that the packer needs no equipment whatever to pack goods in this type of container. While, as described, the end extension flaps 19, 20, 110 23 and 24 are glued to the ends 11 and 12, 115 it is not essential that they be so secured, as the outer band C serves to reinforce the package and hold it securely in assembled position.

While in the above described embodiment of the invention the partial closure flaps are described as connected to the side walls, and the diagonal lines for collapsing the box are likewise formed in the side walls, it is 120 obvious that a similar arrangement might be employed in connection with the end walls, and in the accompanying claims it is to be understood that the terms "side" and "end" walls may be interchanged without 125 130

departing from the spirit of the invention.
What I claim is:

1. A blank for forming a container, comprising a rectangular portion from which the bottom of the container is to be formed, end and side wall portions connected along flexible lines to the said bottom portion, extension flaps hingedly connected to the ends of the side walls, and adapted to be glued to the end walls in the assembled box, partial closure flaps hingedly connected to the side walls along lines parallel to the lines connecting the sides to the bottom, the partial closure flaps being adapted to meet in the assembled box, but having cut-away portions whereby a part of the contents of the finished container will be exposed. 5
2. A blank for forming a container, comprising a rectangular portion from which the bottom of the container is to be formed, end and side wall portions connected along flexible lines to the said bottom portion, extension flaps hingedly connected to the ends of the side walls, and adapted to be glued to the end walls in the assembled box, partial closure flaps hingedly connected to the side walls along lines parallel to the lines connecting the sides to the bottom, the partial closure flaps being adapted to meet in the assembled box, but having cut-away portions whereby a part of the contents of the finished container will be exposed, a flap forming an extension of one of the partial closure flaps and having a securing tab hingedly connected thereto, and a slot formed at the juncture line between the opposite closure flap and the corresponding side wall, which slot is adapted to receive said securing tab when the container is set up and closed. 20
3. A blank for forming a container, comprising a rectangular portion from which the bottom of the container is to be formed, end and side wall portions connected along flexible lines to the said bottom portion, extension flaps hingedly connected to the ends of the side walls, and adapted to be glued to the end walls in the assembled box, partial closure flaps hingedly connected to the side walls along lines parallel to the lines connecting the sides to the bottom, the partial closure flaps being adapted to meet in the assembled box, but having cut-away portions whereby a part of the contents of the finished container will be exposed, and flexible lines extending diagonally inward from the ends of the lines of juncture between the bottom and side walls, across said side walls and partial closure flaps, providing means whereby the container may be collapsed after the side extension flaps have been glued in place. 45
4. A display container comprising a bottom, sides, ends, and partial top closure formed from a single blank, the partial top closure comprising a pair of flaps, hingedly connected to opposite side walls and meeting substantially at the center of the top, the flaps being cut away diagonally toward the ends of the container, leaving triangular openings for the display of the contents of the box. 50
5. A display container comprising a bottom, sides, ends, and partial top closure formed from a single blank, the partial top closure comprising a pair of flaps, hingedly connected to opposite side walls and meeting substantially at the center of the top, the flaps being cut away diagonally toward the ends of the container, leaving triangular openings for the display of the contents of the box, one of said partial closure flaps having an extension reaching to the opposite side wall, and a hinged tab on said extension fitting into a slot on the juncture line between said side wall and the corresponding closure flap. 55
6. A display container adapted to be formed from a single blank of sheet material, comprising a bottom portion carrying side and end walls, closure flaps on the edges of said side walls, said closure flaps being adapted to meet when folded inwardly, in the assembled container, to lie at substantially right angles to their respective side walls, and portions of said closure flaps being partially cut away whereby a part of the contents of the container will be exposed. 60
7. A display container adapted to be formed from a single blank of sheet material comprising a bottom portion carrying side and end walls, closure flaps on the edges of said side walls, said closure flaps being adapted to meet when folded inwardly, in the assembled container, to lie at substantially right angles to their respective side walls, portions of said closure flaps being cut away whereby a part of the contents of the container will be exposed, a locking flap forming an extension on one of said closure flaps, and a slot formed at the juncture of said other closure flap and its respective side wall, said slot being adapted to receive said locking flap to thereby secure said container in set up position. 65
8. A display container adapted to be formed from a single blank of sheet material, comprising a bottom portion carrying side and end walls, closure flaps on the edges of said side walls, said closure flaps being adapted to meet when folded inwardly, in the assembled container, to lie at substantially right angles to their respective side walls, said closure flaps being partially cut away whereby a part of the contents of the container will be exposed, a transparent sheet adapted to overlie the partially open top of said container, and means for frictionally holding said sheet securely in place. 70

place, said means comprising a collapsible band of substantially the same height as said walls and adapted to surround said container.

⁵ Signed at Chicago, Illinois, this 7th day of November, 1930.

JOHN F. HALLADAY.
